UNITED STATES PATENT OFFICE

2,205,297

X-RAY TUBE

Kurt Lenz, Berlin-Lichterfelde, Germany, assignor to General Electric Company, a corporation of New York

Application July 21, 1939, Serial No. 285,816
In Germany July 23, 1938

3 Claims. (Cl. 250—147)

This application relates to improvements in X-ray tubes.

In X-ray tubes provided with an exposed target, electrons reflected from the target surface are free to impinge on the glass wall of the tube envelope. In order to avoid the possibility of damage to the envelope due to this cause it is known to place the target at the inner end of a relatively long channel leading into the interior 10 of the anode so that the target is substantially enclosed by the anode material. In order to prevent escape of electrons, while permitting X-rays to leave in the desired direction, the anode is provided with an outlet channel which is covered 15 at its outer end by a so-called window, such window consisting of a metal layer of such thickness as to intercept high velocity electrons.

In tubes of high capacity the presence of a window of the type above referred to involves 20 considerable difficulty in providing adequate cooling of the window. In this connection it has been proposed to use as a window material a heat-resistant metal which is capable of operating at a temperature so high as to make feasible 25 the dissipation of heat mainly by radiation. In such an arrangement, however, it has been found that thermal conduction from the window to the anode metal at the region where the two are connected tends to produce excessive vaporization of 30 the latter and thus to interfere with the proper functioning of the tube. It is the principal object of my present invention to provide an improved window arrangement by which this difficulty may be overcome.

35 The features of the invention which I desire to protect herein are pointed out with particularity in the appended claims. The invention, itself, together with further objects and advantages thereof may best be understood by reference to 40 the following description taken in connection with the accompanying drawing in which Fig. 1 represents a longitudinal sectional view of an anode embodying the invention; Fig. 2 is a transverse sectional view of the anode of Fig. 1, and 45 Fig. 3 shows schematically the incorporation of the anode of Fig. 1 in a complete X-ray tube.

Referring particularly to Fig. 1, there is shown 50 a portion of an X-ray tube anode designated by the numeral 1. This anode is of a relatively massive construction and consists preferably of a highly conducting metal such as copper. At one end the anode is provided with an open-ended channel 2 which leads into the interior of the anode structure.

55 Within the anode and adjacent the extremity

of the channel 2 there is arranged an inclined target 3 which may consist for example, of a disk of a refractory metal such as tungsten set into the body of the anode. This target is adapted to receive the impingement of a beam (E) of high velocity electrons. It may be cooled by the provision of means such as an inlet pipe 5 for circulating cooling fluid into contact with a portion of the anode structure which is in good heat exchanging relation with the target. As a result 10 of the impingement of electrons on the target 3, X-rays are emitted from the target in all directions. In order to permit such X-rays to leave the structure only along a desired path the anode is provided with a second channel 6 which extends from the vicinity of the target outwardly 15 toward the exterior of the anode. As a result of the existence of this channel there is projected exteriorly of the anode an electron beam which has a region of major intensity within the angle 20 A—B and a penumbral region C—D. In order to prevent the escape through the channel 6 of electrons which are reflected from the target 3 the outer opening of the channel is covered by means of a relatively thin metal foil 8. This foil 25 is preferably constituted of a metal such as tantalum which is capable of operating without evaporation at extremely high temperatures, say, on the order of two thousand degrees centigrade or above. It is secured to the main body of the 30 anode by being soldered or otherwise joined thereto at the peripheral region a.

Without the special provision shortly to be described an arrangement such as that indicated above would have a strong tendency to produce 35 melting of the anode material at the region of contact between such material and the foil 8. The melted material would flow over the surface of the foil and eventually be evaporated onto the walls of the envelope.

In order to prevent this occurrence, means 40 are provided for shielding a perimetrical extending region of the foil from direct radiations proceeding from the target 3. To this end the inner wall of the channel 6 is cut away as indicated at 9 so that there is a region a—b of the foil which is shielded by the anode structure without being in contact therewith. As a result 45 of this arrangement a relatively considerable temperature drop may occur between the central portion b—b of the foil and that part of the foil which is in direct contact with the anode metal. Consequently, even though the central portion of the foil may be operating at a temperature above two thousand degrees centi- 50 55

grade, the outer edges of the foil will be at a temperature below the melting point of copper. In order to permit such a temperature drop to occur, it is of course necessary that the thickness of the foil be relatively small with reference to its effective radiating area. In order to increase the specific radiating capacity of the foil its surface may be modified by roughening or blackening.

10 Fig. 2 shows the window arrangement as viewed in another plane. In order that the radiating area of the foil 8 may be greater than that which would be provided, for example, by a flat surface, it is preferred that the foil be made to follow the outer cylindrical contour of the anode surface as shown. It will be understood that the window as a whole is of generally circular shape.

For the purpose of completeness the anode 20 1 is shown in Fig. 3 in its normal relation to the other parts of an X-ray tube. In the arrangement illustrated the anode is supported at one extremity of a glass envelope 16 by means of a glass-to-metal seal indicated at 11. At the other end of the envelope there is provided a cathode comprising an electron-emitting filament 12. This filament is positioned in a slot 13 provided in a metallic focusing element 14, the latter element being in turn supported by 25 means of a metallic cylinder mounted on a reentrant portion of the glass envelope as indicated at 15. In the operation of the tube, electrons projected from the filament 12 impinge on the target 3 and cause X-rays to be projected 30 in a direction transverse to the axis of the tube through the window 8.

What I claim as new and desire to secure by Letters Patent of the United States is:

1. An X-ray tube including a cathode, an 40 anode having an open ended channel directed toward said cathode, an X-ray-producing target positioned within said anode at the inner extremity of said channel, a second channel extending from the vicinity of said target toward 45 the exterior of the anode in a direction of desired X-ray emission and a window arrangement for preventing the escape of electrons through said second channel, said window arrangement comprising a relatively thin foil of a refractory 50 metal having a melting temperature materially

above that of the material of which the main body of the anode is constituted and at least on the order of 2,000 degrees centigrade, whereby the foil may be heated to a temperature of effective heat radiation without vaporization thereof, the said foil being joined at its outer edges to the main body of the anode so as to close the outer end of the channel, and means physically spaced from the foil for shielding a perimetrically extending portion thereof from the impact of 10 electrons, thereby to prevent such portion of the foil from attaining a temperature in excess of the melting point of the anode material and thus producing vaporization of the contiguous parts of the anode structure. 15

2. An X-ray tube including a cathode, an anode having an open ended channel directed toward said cathode, an X-ray-producing target positioned within said anode at the inner extremity of said channel, a second channel extending 20 from the vicinity of said target toward the exterior of the anode in a region of desired X-ray emission and a window arrangement for preventing the escape of electrons through said second channel, said window arrangement comprising a relatively thin foil of a refractory metal having a melting temperature materially above that of the material of which the main body of the anode is constituted and at least on the order of 2,000 degrees centigrade, whereby the 25 foil may be heated to a temperature of effective heat radiation without vaporization thereof, the said foil being joined at its outer edges to the main body of the anode so as to close the outer end of the channel, and means extending inwardly from the wall of the channel at a point 30 displaced from the foil for shielding a perimetrically extending portion of the foil from direct radiations from said target, thereby to prevent such portion of the foil from attaining a temperature in excess of the melting point of the anode material and thus producing vaporization of the contiguous parts of the anode structure. 35

3. An X-ray tube according to claim 1 characterized by the fact that the surface of the window foil is blackened or roughened to increase the heat radiating capacity thereof. 40 45
